UNITED STATES PATENT OFFICE.

FRANK N. ETHRIDGE, OF BOSTON, MASSACHUSETTS, ASSIGNOR TO THE AMERICAN POSTAL MACHINES COMPANY, OF SAME PLACE.

MACHINE FOR MARKING MAIL-MATTER.

SPECIFICATION forming part of Letters Patent No. 449,363, dated March 31, 1891.

Application filed November 1, 1890. Serial No. 370,069. (No model.)

To all whom it may concern:

Be it known that I, FRANK N. ETHRIDGE, of Boston, in the county of Suffolk and State of Massachusetts, have invented certain new and useful Improvements in Machines for Marking Mail-Matter, of which the following is a specification.

This invention has for its object to provide a simple and efficient machine adapted to rapidly and accurately apply postmarks and stamp-canceling marks to pieces of mail-matter; and it consists in the several improvements which I will now proceed to describe and claim.

15 Of the accompanying drawings, forming a part of this specification, Figure 1 represents a front elevation of a machine embodying my invention. Fig. 2 represents an end elevation of the same. Fig. 3 represents a top view. Fig. 4 represents a horizontal section through the impression-roll and its carrying-shaft and the head that carries the printing-form, said section being taken on the plane of line 44, Fig. 5. Fig. 5 represents a vertical section through said parts, taken on line 55, Fig. 4. Figs. 6 and 7 represent sections on line 44, Fig. 5, showing the conditions at different stages of the operation. Fig. 8 represents a section showing a modification of the construction shown in Figs. 6 and 7.

The same letters and numerals of reference indicate the same parts in all the figures.

In the drawings, *a* represents a horizontal bed or table, which rests on a supporting-frame *b*.

c represents a positively-rotated vertical shaft, which extends upwardly through the table *a* and has affixed to it above said table a circular head *d*, which comprises a segmental printing-form *2*, which includes a portion of the periphery of the head, the remaining portion of said periphery being in the nature of a feeding-surface, so that the head in making a complete rotation will co-operate 45 with an impression-roll, presently described, in printing and positively feeding a letter or other piece of mail-matter which is inserted between the meeting portions of said head and impression-roll.

50 *e* represents another vertical shaft which projects upwardly through the table *a*.

f represents an impression-roll, which is mounted loosely upon the shaft *e*, its periphery being arranged to co-operate with the head *d* in printing and positively feeding letters, as hereinafter described. 55

g represents a clutch, which is movable in a recess in the impression-roll *f*, and is adapted to bear on a collar or enlargement *h*, formed on or rigidly attached to the shaft *e*. When 60 said clutch is pressed inwardly and bears on said collar *h*, the impression-roll *f* becomes engaged with the shaft and rotates therewith; but when pressure is removed from said clutch the impression-roll becomes loose, so 65 that it remains motionless upon the shaft, the roll being separated from the shaft by means of a bearing or fixed collar *i*, Fig. 5, projecting upwardly from the table into a circular cavity at the center of the impression-roll, as 70 shown in Figs. 4 and 5.

g' represents an arm or lever, which is pivoted at *g* to the impression-roll and has its inner end formed as a cam bearing against the back of the clutch *g*. (See Fig. 4.) Said 75 arm projects outside of the periphery of the impression-roll and across the space between the impression-roll and the head *d*, into which a letter enters preparatory to being grasped, positively fed, and printed by the action of 80 said head and impression-roll.

When the arm *g'* is in the position shown in Fig. 4, it exerts no pressure upon the clutch *g*, so that the impression-roll is loose upon the shaft *e* and does not rotate. 85

The machine is provided with means, hereinafter described, for yieldingly moving a letter *k* toward the meeting-point of the head *d* and the impression-roll *f* and yieldingly pressing said letter against the arm *g'*. When the 90 letter is thus pressed against said arm, it swings the outer end of the same toward the head *d* and into a peripheral groove or recess *3*, formed in said head. Said recess extends nearly around the circumference of the head, 95 but is interrupted at one side by a protuberance having two surfaces *7* *8*, the surface *7* being within the periphery of the head and hereinafter called a "shoulder," while the surface *8* is on the periphery of the head and 100 is hereinafter called a "peripheral" surface. After the arm *g'* is moved into the recess *3* by

the forward movement of the letter *k* the shoulder *7* strikes said arm, as indicated in Fig. 6, and moves it in the direction required to cause its inner end to firmly press the clutch *g* against the collar on the shaft *e* and thus lock the impression-roll to said shaft, so that the roll commences to rotate with the head *d*, the two shafts *c* and *e* being rotated in opposite directions by means hereinafter described. The head *d* and the impression-roll *f* are thus caused to act to positively feed the letter *k* forward and print the same, the printing-form coming into contact with the letter, as will be readily seen.

15 It should be here mentioned that the yielding feed movement imparted to the letter *k* by the feeding device, to be presently described, causes the letter to follow the arm *g'* until it is grasped by the meeting surfaces of 20 the head *d* and impression-roll *f*.

When the head *d* and impression-roll *f* have made nearly a complete rotation from the position shown in Fig. 6, the peripheral surface *8* of the head *d* comes in contact with 25 the outer end of the arm *g'*, as shown in Fig. 7, and moves said arm backwardly, thus causing it to release the clutch *g* and instantly disengage the impression-roll from the shaft *e*, said peripheral surface *8* acting at the same 30 time as a stop, which, through the arm *g'*, checks the momentum of the impression-roll, so that the latter is instantly stopped, the arm *g'* remaining in the position shown in Fig. 7, ready to be acted upon by the next 35 letter. It will be seen, therefore, that a letter approaching the head *d* and impression-roll *f* cannot be engaged by said head and roll and moved positively forward until the shoulder *7* of the head comes into position to 40 strike the arm *g'*. Hence the printing-form always acts on the letter at a given distance from its advancing end. In case the peripheral surface *8* is in position to support the arm *g'* when it is first moved by the contact of 45 the advancing letter with it, said letter, which is moved yieldingly, is retarded for the brief period required to carry the peripheral surface away from the arm *g'* and then presses said arm into the recess, where it awaits the 50 arrival of the shoulder *7*.

I do not limit myself to the details of the clutch device here shown and described, and may adapt the projecting arm *g'* to operate the clutch in any suitable way, or the said 55 arm itself may constitute the clutch by the bearing of its inner end upon the shaft *e* or the collar *h* thereof, as shown in Fig. 8.

m represents an inking-roll, which is mounted upon a stud *m'*, affixed to a swinging 60 frame *m²*, which is pivoted at *m³* to an ear on the table *a*. A spring *m⁴*, bearing on the arm *m²*, presses the inking-roll yieldingly against the periphery of the head *d*.

The shaft *c*, carrying the head *d*, is journaled in bearings *n n'* on the swinging ends of arms *n² n³*, which extend from a hub *n³*, mounted to oscillate on a fixed stud attached

to the table. Said arms and hub constitute a swinging frame, which enables the shaft *c* and the head thereon to swing toward and 7c from the impression-roll, and thus permit letters of any thickness to pass between said head and roll. A spring *n⁴*, attached at *n⁵* to the table and bearing at one end against the bearing *n*, presses the head *d* toward the 75 impression-roll. The shaft *e*, carrying the impression-roll *f*, is journaled in a bearing *o*, attached to the frame *b* below the table, and in a collar or bearing *i*, already described, secured to the table. Said shafts *c* and *e* are 80 positively rotated by gearing connecting them with a driving-shaft *p*, said gearing comprising a gear *q* on the driving-shaft, a gear *q'* on a short shaft *q²*, an intermediate gear *q³*, connecting the gears *q* and *q'*, a bevel-gear *q⁴* 85 on the shaft *q²*, a bevel-gear *q⁵* on the shaft *e*, and intermeshing gears *q⁶ q⁷*, affixed, respectively, to the shafts *c* and *e*. The shaft *p* may be rotated by a driving-belt running on a pulley *p'* or in any other suitable way. 90

The feeding device which yieldingly feeds the letters to the printing and positive-feeding mechanism above described is a spiral conveyer *r*, which is attached to a shaft *r'*, arranged substantially at right angles with 95 the path of movement of a letter toward the meeting-point of the impression-roll and head *d*. The convolutions of said conveyer are partly below and partly above the table, and the conveyer is positively rotated by means 100 presently described.

Above the conveyer is a mouth or hopper *s*, into which the letters to be marked may be dropped by an attendant, said mouth being arranged to guide the letters so that they will 105 drop edgewise between the convolutions of the conveyer and stand vertically, or nearly so, between said convolutions. The conveyer is rotated in the direction indicated by the arrows in Figs. 1 and 3, and is caused to give 110 the letters a combined lateral movement, resulting from the spiral form of the conveyer, and an endwise movement toward the printing and positive-feeding devices, caused by the frictional contact of the sides of the 115 convolutions of the conveyer with the sides of the letters. The letters are thus fed yieldingly toward the head *d* and impression-roll *f*, with the result above described when the letters come in contact with the arm *g'*. The 120 conveyer *r* is arranged so that the combined lateral and endwise movement it gives the letters will move the advancing end of each letter first into contact with the arm *g'* and then to the meeting-point at the head *d* and impression-roll *f*. The letters that are printed and fed positively forward by said printing and positive-feeding mechanism enter a packing device, which consists of another 125 spiral conveyer *t*, mounted upon a shaft *t'*, which is substantially parallel with the shaft *r'* of the feeding-conveyer. The convolutions of the conveyer *t* are located partly below and 130 partly above the table *a*, and said convolu-

135

tions are preferably of the varying sizes shown in Fig. 3, they being smaller at one end of the conveyer and of gradually-increasing diameter for a portion of the length of the conveyer, 5 and then gradually decreased in diameter to the delivering end of the conveyer. This form is shown and described in Letters Patent No. 441,832, dated December 2, 1890, Serial No. 363,241. The shaft t' and the conveyer thereon are rotated in unison with the shaft r' and the conveyer r by means of suitable gearing connecting said shafts to the driving-shaft.

The letters fed forward by the joint action 15 of the impression-roll f and head d move endwise between the convolutions of the packer t at the smaller end thereof, said letters being guided and prevented from falling over away from the conveyer t by means of a wall u , 20 which extends along parallel with the path in which the letters are moved by the head d and impression-roll f . A wall u' , extending at right angles with the wall u and preferably formed as a continuation of the latter, 25 acts to arrest the endwise movement of the letters when they have entered the spaces between the convolutions of the conveyer t and prevents the letters from moving too far across said conveyer. The letters are moved by the 30 conveyer t and packed upon a shelf or extension extending outwardly from the table a at a' , Fig. 3.

It will be seen that the mechanism above described is extremely simple, so that the machine is likely to be durable and not easily deranged.

The shafts r' t' are provided, respectively, 40 with bevel-gears r^2 t^2 , meshing with gears w' w^2 on a shaft w , which is journaled in a fixed bearing w^3 on the supporting-frame, and is provided with a gear x , meshing with the gear q on the shaft p , as shown in Fig. 3. To assist in the presentation of the letters to the arm g' and to the meeting-point of the roll f 45 and head d , I secure to the shaft or impression-roll driver e a pulley e^2 , which rotates continuously with said shaft above the impression-roll. Said pulley e^2 is arranged so that each letter moved forward by the conveyer r comes in contact with the moving 50 periphery of the pulley, the latter aiding the conveyer in moving the letter along to the arm g' and to the meeting-point of the roll f and head d .

55 I claim—

1. In a machine for marking mail-matter, the combination, as a means for printing and positively feeding letters, &c., of a rotating shaft or driver, a roll normally loose thereon 60 and provided with a shaft-engaging clutch and an operating-arm therefor projecting from the periphery of the roll, said arm being adapted to be moved by a letter advancing toward it, a rotating roll or head arranged 65 to co-operate with the first-mentioned roll and provided with two operating-surfaces,

one of which is within and the other upon its periphery, said surfaces being arranged to co-operate, as described, with the clutch-operating arm in alternately engaging the clutch 70 with and disengaging it from said shaft or driver, a printing-form attached to one of said rolls, and a segmental impression-surface on the other roll, as set forth.

2. In a machine for marking mail-matter, 75 the printing and positive-feeding mechanism consisting of a rotating shaft or driver, an impression-roll normally loose thereon and provided with a shaft-engaging clutch and an operating-arm therefor projecting from 80 the periphery of the roll, said arm being adapted to be moved by a letter advancing toward the impression-roll, and a rotating head arranged to co-operate with said roll and provided with a printing-form and with two 85 operating-surfaces, one of which is within the periphery of the head and acts on the arm after its movement by a letter to engage the clutch and the impression-roll with its shaft, the other operating-surface being on 90 the periphery of said head and acting on the arm to disconnect the impression-roll from its shaft and stop the rotation of said roll, all combined substantially as set forth.

3. The combination, with the letter-printing and positive-feeding mechanism comprising the rotating shaft or driver, the loose impression-roll thereon provided with a clutch and with a clutch-operating arm, and a rotating head having a printing-form and two 100 clutch-operating surfaces, as described, of the feed-pulley affixed to the impression-roll-operating shaft above said roll, and a letter-feeding device arranged to co-operate with said pulley in presenting a letter to the clutch-operating arm and to the meeting-point of the impression-roll and head, as set forth. 105

4. In a machine for marking mail-matter, a circular head affixed to a rotating shaft and provided with a segmental printing-form constituting a part of the periphery of the head, 110 said head having a peripheral recess interrupted by a shoulder within the periphery of the head and a peripheral surface forming a part of the said periphery, combined with a 115 rotating shaft in suitable proximity to said head, an impression-roll loosely mounted on said shaft and carrying a clutch adapted to engage the said roll with and disengage it from the shaft, and an arm or lever pivoted 120 to the said roll and engaged at its inner end with the clutch, its outer end projecting outside the periphery of the roll within the path of a letter approaching the said head and roll, 125 said lever being arranged to be moved by the approaching letter into the path of the shoulder on the head and by said shoulder into position to engage the clutch with the shaft supporting the impression-roll, whereby the impression-roll is rotated with the head and 130 printing-form until the said peripheral surface of the head meets the lever and through

the latter disengages the clutch from shaft and stops the rotation of the impression-roll, as set forth.

5. In a machine for marking mail-matter, the combination of a supporting bed or table, letter-printing and positive-feeding mechanism, located over the table and composing a rotating printing-form and a rotating impression-bed, a yielding letter-feed consisting of 10 a spiral conveyer arranged partly below and partly above said table, its axis being substantially at right angles with the path of a letter between said printing-form and impression-roll, and means for rotating said conveyer, whereby its convolutions are caused to yieldingly present letters dropped between them to the printing and positive-feeding mechanism, as set forth.

6. The combination of a bed or table, a printing and positive-feeding mechanism above said table, comprising a rotating head having a printing-form, an impression-roll, a rotating shaft on which said roll is loosely mounted, and a movable arm or lever projecting from 20 the periphery of the impression-roll to operate a clutch which connects said roll with and disconnects it from its shaft, the printing-head having surfaces arranged to co-operate, as described, with said arm, a spiral conveyer 25 arranged partly below and partly above said table and arranged as described relatively to the printing mechanism, and means for rotating said conveyer, whereby its convolutions are caused to yieldingly press a letter dropped between them first against the said arm to displace the latter and then to the point where the head and roll grasp the letter, as set forth.

7. In a machine for marking mail-matter, 30 the combination of a bed or table, two spiral conveyers arranged with their convolutions partly below and partly above said table, their axes being substantially parallel, one of said conveyers constituting a yielding 35 letter-feed and the other a packer, and a printing and positive-feeding mechanism located between said conveyers and comprising a rotating head having a printing-form and a rotating impression-roll, said mechanism being arranged to receive letters from 40 the feeding-conveyer and to present the letters after printing to the packing-conveyer, as set forth.

8. In a machine for marking mail-matter,

the combination of the rotating shaft or driver, 55 the normally-loose impression-roll upon said shaft, having a clutch adapted to connect it with and disconnect it from the shaft and an outwardly-projecting clutch-operating arm, the letter-feeding pulley or disk affixed to the 60 said shaft or driver above the impression-roll, the continuously-rotating head arranged to co-operate with the impression-roll in grasping and positively feeding a letter, said head having a printing-form constituting a 65 part of its periphery, a peripheral groove above said form adapted to receive the said clutch-operating arm and two surfaces interrupting said groove, one being a shoulder within the periphery of the head and the 70 other a portion of said periphery, said surfaces being adapted to co-operate, as described, with the clutch-operating arm in engaging the impression-roll with and disengaging it from its shaft or driver, a bed or 75 table arranged to support the lower edge of a letter in suitable relation to said head and impression-roll, a spiral conveyer located partly below said table and presenting portions of its convolutions above the table, and means for rotating said conveyer, whereby it is caused to feed a letter forward to the said feeding pulley or disk and to co-operate with the latter, first, in pressing the letter against the clutch-operating arm to force the latter 80 into the groove in the rotating head, and, secondly, in presenting the letter to the meeting-point of the impression-roll and head after the impression-roll has been set in motion, as set forth.

9. The letter-supporting bed or table, the spiral conveyer arranged with its convolutions partly above said table, and the letter-printing and positive-feeding devices arranged above said table to receive letters fed 95 forward by said conveyer, combined with a guide or hopper located above said conveyer and adapted to guide letters into the spaces between the convolutions of the conveyer, as set forth.

In testimony whereof I have signed my name to this specification, in the presence of two subscribing witnesses, this 18th day of October, A. D. 1890.

FRANK N. ETHRIDGE.

Witnesses:
